UNITED STATES PATENT OFFICE.

JAMES L. SMITH, OF TUSCOLA, ILLINOIS.

IMPROVEMENT IN VENTILATORS.

Specification forming part of Letters Patent No. 42,606, dated May 3, 1864.

To all whom it may concern:

Be it known that I, J. L. SMITH, of Tuscola, Douglas county, in the State of Illinois, have invented certain new and useful Improvements in Ventilators; and I hereby declare that the following is a true and exact description of the same, reference being had to the accompanying drawings, and to the letters of reference marked thereon.

The object of my invention is to furnish a supply of fresh air in a close room when vitiated by respiration, and also to afford a vent to the deoxidized air.

Figure 1 in the annexed drawings represents a vertical section of my ventilator. Fig. 2 is a plan view of the same with the top removed.

The letter A represents the body of the machine, which is made of plate metal and of an oblong form. The door which is made to open for inspection is designed before the ventilator is placed in position to be soldered tightly, so as to exclude the air. The ventilator is then inserted in the wall and surrounded by the material of which the wall is built.

The pipe B is made to pass through the wall in order to conduct the fresh air from without into the compartment marked C, Fig. 2.

D represents a pipe which has a sliding valve on the end. The pipe D is placed near the bottom of compartment C, and intended

to convey the fresh air from C into the room requiring ventilation. The quantity of air admitted into the room is to be regulated by the sliding valve e on pipe B and the valve g on pipe D.

E in Fig. 1 represents a pipe which projects into the room, and is constructed with a sliding valve at its end similar to the one on D. The pipe E is placed near the top of compartment F, and is designed to carry off the vitiated air, first, into chamber F, and thence into pipe H, which conducts it upward through the roof, where it escapes.

By this simple apparatus the air in a small and crowded apartment may be kept perfectly pure and the evil effects avoided of breathing an atmosphere deprived of its proper proportion of oxygen.

Having thus described my invention, what I claim, and desire to secure by Letters Patent, is—

The compartments C and F, in combination with pipes B, H, E, and D, the whole constructed in the manner and for the purpose herein set forth.

In testimony that I claim the foregoing I hereby affix my signature in the presence of two witnesses.

JAMES L. SMITH.
